[57] CLAIM

The ornamental design for fitting for drawer slide assembly, as shown and described.

DESCRIPTION

FIG. 1 is a perspective view of a fitting for a drawer slide assembly showing our design;

FIG. 2 is a perspective view showing the end not disclosed in FIG. 1;

FIG. 3 is a top plan view;

FIG. 4 is a side elevational view; and

FIG. 5 is an end elevational view looking in the direction of the arrows shown in FIG. 1.
The side of the fitting not shown is a mirror image of the side shown in FIG. 4.

The dot-dash lines depicting a drawer slide fragment in FIG. 1 are for illustrative purposes only.
